UNITED STATES PATENT OFFICE

WLADYSLAW JASINSKI, OF CHICAGO, ILLINOIS

WALKING CANE

Application filed October 3, 1929. Serial No. 397,031.

This invention relates to improvements in walking canes of the type disclosed in my Patent 1,145,994 patented July 13, 1915.

The primary object of this invention is to provide a walking cane with a longitudinally split handle which may be folded on a hinge joint to a horizontal position for forming a temporary seat.

A still further object of this invention is to provide a device of the above mentioned character, having a novel form of holding means for holding the split handle in a closed position whereby the device may be used as a walking cane.

A still further object of this invention is to provide a device of the above mentioned character having changes in structural details as well as many novel features which combine to form a compact and neat appearing combined walking stick and temporary seat.

Other objects and advantages of the invention will become apparent during the course of the following description forming a part of this specification and illustrated in the accompanying drawings and set forth in the appended claims.

In the drawings like characters are employed to designate corresponding parts throughout the several views, Figure 1 is a vertical side elevational view of the walking stick showing the folding handle in its position to be used as a handle for a walking stick.

Figure 2 is a somewhat similar view showing the foldable handle raised from its joint ready to be extended in position to be used as a temporary seat.

Figure 3 is a vertical rear elevational view showing the foldable handle in its completely extended position to be used as a temporary seat.

Figure 4 is a vertical fragmentary sectional view illustrating the manner of supporting the hinged handle sections, the sliding shank to which the handle sections are secured and the means for limiting the longitudinal movement of the shank.

Figure 5 is a vertical cross sectional view from lines 5—5 of Figure 3 illustrating the formation of the walking stick and the shank

for holding the handle portions in their respective positions.

Figure 6 is a fragmentary top elevational view of the invention showing the hinge joint between each of the foldable handle sections and the sliding shank, and Figure 7 is a transverse cross sectional view taken on lines 7—7 of Figure 1 illustrating the construction of each foldable handle section.

Referring more in detail to the drawings, the reference character 10 designates the longitudinal shaft portion of a walking stick, which is formed by sections 11 and 12 held together by a tip 13 and a ferrule 14 at the upper end thereof. The handle portion of the cane 10 is arcuately curved and is formed by complementary sections 15 and 16 having a core formed of metal or composition sections 17 and 18 covered by bakelite sections 19 and 20.

Each of the handle sections 15 and 16 are provided with bifurcated ears 22 adapted to be hinged to a sliding shank 23 at the uppermost end thereof by means of pins 24. The sliding shank 23 is formed of a flat piece of metal tapering from its uppermost end to its lower portion, and is provided with a longitudinal slot 25 formed in the intermediate portion of the shank and a depression 23a is formed at the lower portion of the shank. The sliding shank 23 is adapted to be received in cutaway portions of each of the complementary faces of the cane sections 11 and 12 whereby an opening 26 is formed which tapers from the metal ferrule 14 downwardly where it terminates adjacent a further cutaway portion 27 in the cane section 11 wherein is received a spring finger 28 having a projecting portion 29 adapted to be received in the depression 23a of the shank 23. The uppermost portion of the opening 26 is enlarged as at 30 to receive the bifurcated ears 22 of the handle sections 15 and 16, as more clearly shown in Figure 5.

A retaining pin 31 extends between the sections 11 and 12 of the cane 10 and passes through the longitudinal slot 25 of the shank 23 for limiting the vertical movement thereof, when the handle sections 15 and 16 are

extended in the position shown in Figures 3 and 4 for forming a temporary seat.

- When the handle sections 15 and 16 are folded into the position shown in Figures 3 and 4, the sliding shank 23 is pulled upwardly until it is stopped by the pin 31 and the handles 15 and 16 are adapted to be supported by the edges 32 and 33 of the ears 22, upon the upper edge 21 of the metal ferrule 14.
- 10 When it is desired to use the device as a conventional form of walking stick the handle sections 15 and 16, are folded in the position shown in Figure 2 and pushed downwardly to cause the sliding shank 23 and the
- 15 depression 23a to be moved down into engagement with the projection 29 of the spring finger 28.

It is to be understood, that while the form of the invention herein shown and described 20 is to be taken as a preferred embodiment of the same and that minor changes may be made without departing from the spirit of the invention or the scope of the subjoining claims.

What I claim is:—

- 25 1. A folding walking cane of the character described comprising a two part cane, having a longitudinal rectangular opening in the upper center of the cane formed by mating flat walled depression in the two part, said opening being tapered from its upper end to its lower end, a tapered flat metal shank slidably mounted in the longitudinal opening, a pair of similarly shaped handle sections hinged to the upper end of the shank having complementary faces, adapted to be folded to present the complementary faces to each other and forming a seat when in their extended position, said opening being laterally enlarged at its lower end, a spring catch set into 40 the lateral enlargement for engagement with the lower end of the shank to retain the device in cane formation, and means for limiting the longitudinal movement of the sliding shank.
- 45 2. A folding cane seat of the character described comprising a cane having a central longitudinally tapered opening extending from the top thereof to nearly the central portion of the cane, a flat metal tapered shank 50 having a depression in its lower end slidably mounted in the longitudinal opening, a pair of handle sections adapted to be unfolded into a seat and respectively hinged to the upper end of the sliding shank, a spring finger 55 mounted in the lower end of the central longitudinal opening adapted to engage the depression formed in the lower end of the shank, for holding the shank in the opening whereby the handle sections will be held together to form one handle and means for limiting the outward opening of the shank when the handle sections are used as a seat.

In testimony whereof I affix my signature.

WLADYSLAW JASINSKI.
